HONING DEVICE FOR SHEARS

Vernon J. Veron, Portland, Oreg.

Application October 18, 1937, Serial No. 169,574

11 Claims. (Cl. 51—221)

My invention relates to improvements in a honing device for shears wherein I provide means whereby a pair of shears may be accurately positioned and manipulated relative to the cutting 5 surface of a hone.

My device is of special value to barbers, dress-makers, surgeons and others to whom properly and frequently sharpened shears are a necessity. As ordinarily sharpened, such shears require the 10 services of an expert grinder at comparatively short intervals, and the cost of keeping such shears properly sharpened represents a very considerable item of expense. With my new and improved device such sharpening can be effected 15 by ordinary labor and with assurance of securing a satisfactory result.

Where by device is available for use shears may be reconditioned at shorter intervals than would ordinarily be done. My device may be 20 used by the ordinary shear user thus eliminating the necessity for employing a professional grinder. In this way the quality of the cutting edge of the shears may be kept at a consistently high level, instead of varying with use where 25 they are resharpened only after having become so dull that such resharpening is a necessity.

The coarseness of the cutting edge may be changed to suit the individual, by the use of a hone with a coarse or fine grit as may be required. I find that the cutting edge produced 30 by use of a hone with a coarse grit will cut some materials better than a cutting edge produced by use of a hone with a fine grit, and that the cutting edge produced by use of a hone with fine 35 grit will cut some other materials better than a cutting edge produced by use of a hone with a coarse grit.

With these and incidental objects in view, the invention consists in certain novel features of 40 construction and combination of parts, the essential elements of which are set forth in the appended claims, and a preferred form of embodiment of which is hereinafter shown with reference to the drawings which accompany and 45 form a part of this specification.

In the drawings:

Fig. I is a perspective top front view of the holder illustrating a pair of shears disposed within the holder and being honed upon a suitable 50 stone.

Fig. II is a perspective plan view of the mechanism illustrated in Fig. I.

Fig. III is an end view of the holder.

Fig. IV is a back view of the body element.

Like reference characters refer to like parts throughout the several views.

I preferably make the body element 1 of a single piece of sheet metal and I make the same as having an adjustable clamp and having a fixed 5 abutment.

I have illustrated the body element as made of a single piece of sheet metal. The body element comprises a relatively broad surface 3 that is normally inclined to the horizontal. 10

A rear wall 4 downwardly extends from the inclined top, the function of which is to hold the blade of the shear being sharpened in an angle to the abrading surface 15 of the hone 14, so that a beveled cutting edge may be obtained. 15 The rear wall 4 is in the form of a depending skirt that is formed integral with that of the body element. Inasmuch as the angle of the bevel on the cutting edge 12 is determined by the height of the rear wall 4, various angles of bevel may 20 be obtained by making the rear wall adjustable so that the height thereof may be changed. One way by which such an adjustable rear wall may be obtained is to provide a wearing plate 5, removably secured to the lower end of the downwardly extending rear wall 4. The wearing plate 5 may be secured to the rear wall 4 in any suitable manner. I have found that satisfactory results are to be obtained where the wearing member 5 is held by frictional engagement between the inside walls 6 and 7. By varying the width of the wearing member the angle of the bevel is varied accordingly. 25

The keenness of the cutting edge 12 is dependent principally upon the rigidity of the shear blade being sharpened at the predetermined angle obtained by the rear wall. 30

Downward movement of the shear blade being sharpened is prevented by the abrading surface and other elements hereinafter described. Upward vertical movement of such shear blade is prevented by a stop 8 which is formed from the body element, and other elements. The cutting edge 12 of the shear blade to be sharpened extends sufficiently beyond the terminal edge 13 40 of the body element so that the cutting edge 12 of the shear blade will contact the hone 14 and will maintain the terminal end 13 of the body element out of engagement with the honing surface 15 of the hone 14. 45

The contour 30 of the lower edge of the body element is shaped to fit the back 31 of the shear blade being sharpened and is shaped to form two stops 20 and 21. These stops 20 and 21 closely fit the V-shaped apertures between the 50 55

pivot of the shear blades and the handles thereof when such blades are opened.

The stop 20 fits the V-shaped aperture seen on top in Fig. I at that point, and stop 21 fits 5 the V-shaped aperture formed below, when the shear blades are in the position shown in Fig. I and Fig. II. Such stops prevent upward and downward movement of the shears at that point, prevent longitudinal movement of the shears toward stop 9, and maintain the shear blades in 10 an open position.

A stop 9 is formed from the body element and is shaped and positioned to maintain the handle 11 of the shear blade being sharpened. Stop 9 15 is forked as disclosed in Fig. I, and prevents upward, downward and inward, that is toward the rear wall, movements of the handle 11.

A stop 16 is also formed integral with the body element 1 and is shaped to maintain the handle 20 17 of the shear blade not being sharpened. It is so positioned that the shear blade not being sharpened will be held out of contact with the hone. This stop prevents an upward movement 25 of the handle, thus maintaining the shear blade being sharpened in a fixed plane. Inasmuch as such handle rests on the body element 1, downward movement of the handle is prevented by the body element. Longitudinal movement of the shears toward stop 9 is also prevented by stop 16.

Means must be supplied to prevent longitudinal 30 movement of the shears in direction toward stop 8, as the device with the shears in position, is drawn across the abrading surface. In addition, means must be supplied to prevent outward movement from the body element, if the device with 35 the shears in position, is lifted away from the abrading surface for another stroke over such surface. Both movements may be prevented by manually holding the shears in position and 40 against the stops. However, I find it more satisfactory to prevent such movements by mechanical means. I find one satisfactory method is to make the stop 9 hold the handle 11 by spring tension jaws. Stop 16 likewise has spring tension 45 to hold handle 17.

I find it more satisfactory to prevent the movements mentioned in the preceding paragraph, to 50 clamp the handles 11 and 17 by means of an adjustable clamp. Such clamp 2 is securable to the body element, and has jaws 2A and 2B disposed adjacent to its front edge. The jaw 2A engages 55 the shear handle 17, and the jaw 2B engages the shear handle 11. The clamp 2 is furcated at its rear and a clamping screw 18 is threaded to the body element and passes between the furcated jaws.

In use, the shear blades are opened; the back 60 of one of the shear blades is placed against the lower edge 30 of the body element and under stop 8; stops 20 and 21 engage the V-shaped 65 apertures between the pivot of the shear blades and the handles thereof; the handle 11 is positioned in stop 9; the handle 17 is positioned in stop 16. If the clamp 2 is used, jaw 2A is placed 70 to hold handle 17 against the stops 16, 20 and 21 and jaw 2B is placed to hold handle 11 against stops 9, 20 and 21 and to hold the shear blade against the lower edge 30 of the body element and under stop 8. The shears are thus held in an extremely rigid and locked position for being honed.

While the form of mechanism herein shown and described is admirably adapted to fulfill the objects primarily stated, it is to be understood 75 that it is not intended to confine the invention to

the embodiment herein shown and described, as it is susceptible of embodiment in various forms, all coming within the scope of the claims which follow.

What I claim is:

1. In a device of the class described, the combination of a body element made of a single piece the top surface of which is inclined upwardly from its front edge, the front edge of which forms an abutment against which the back of the shear blade rests, an adjustable rear wall which depends from the rear edge of the body element, a stop formed from the body element against which the inside of the shear blade being sharpened rests, a stop fashioned to engage the V-shaped aperture formed by the back of the shear blade being sharpened and the handle of the shear blade not being sharpened when the blades are open, a stop fashioned to engage the V-shaped aperture formed by the back of the shear blade 20 not being sharpened and the handle of the shear blade being sharpened when the blades are open, a stop formed from the body element and fashioned to receive the handle of the shear blade being sharpened, a stop formed from the body 25 element fashioned to receive the handle of the shear blade not being sharpened, and an adjustable clamping holder having a jaw disposed at one of the sides which is adapted to engage the handle of the shear blade not being sharpened, 30 and having a jaw disposed at the other side which is adapted to engage the handle of the shear blade being sharpened.

2. In a device of the class described, the combination of a body element made of a single 35 piece the top surface of which is inclined upwardly from its front edge, the front edge of which forms an abutment against which the back of the shear blade rests, an adjustable rear wall which depends from the rear edge of the 40 body element, a stop formed from the body element against which the inside of the shear blade being sharpened rests, a stop fashioned to engage the V-shaped aperture formed by the back of the shear blade not being sharpened and the handle of the shear blade being sharpened when the blades are open, a stop formed from the body 45 element and fashioned to receive the handle of the shear blade being sharpened, a stop formed from the body element fashioned to receive the handle 50 of the shear blade not being sharpened, and an adjustable clamping holder having a jaw disposed at one of the sides which is adapted to engage the handle of the shear blade not being sharpened, and having a jaw disposed at the 55 other side which is adapted to engage the handle of the shear blade being sharpened.

3. In a device of the class described, the combination of a body element made of a single piece the top surface of which is inclined upwardly from its front edge, the front edge of which forms an abutment against which the back of the shear blade rests, an adjustable rear wall which depends from the rear edge of the body element, a stop formed from the body element against which the inside of the shear blade being sharpened rests, a stop fashioned to engage the V-shaped aperture formed by the back of the shear blade being sharpened and the handle of the shear blade not being sharpened when the 60 blades are open, a stop fashioned to engage the V-shaped aperture formed by the back of the shear blade not being sharpened and the handle of the shear blade being sharpened when the 65 blades are open, a stop formed from the body ele- 70

fix the handle of the shear blade being sharpened, a stop formed from the body element with a spring tension jaw and fashioned to receive and fix the handle of the shear blade not being sharpened.

11. In a device of the class described, the combination of a body element made of a single piece the top surface of which is inclined upwardly from its front edge, the front edge of which forms 10 an abutment against which the back of the shear blade rests, an adjustable rear wall which depends from the rear edge of the body element, a stop formed from the body element against which the inside of the shear blade being sharpened 15 rests, a stop fashioned to engage the V-shaped aperture formed by the back of the shear blade

being sharpened and the handle of the shear blade not being sharpened when the blades are open, a stop fashioned to engage the V-shaped aperture formed by the back of the shear blade not being sharpened and the handle of the shear blade being sharpened when the blades are open, 5 a stop formed from the body element fashioned to receive the handle of the shear blade not being sharpened, and an adjustable clamping holder having a jaw disposed at one of the sides which 10 is adapted to engage the handle of the shear blade not being sharpened, and having a jaw disposed at the other side which is adapted to engage the handle of the shear blade being sharpened.
